UNITED STATES PATENT OFFICE.

WILLIAM P. LOWTHER, OF SPOKANE, WASHINGTON.

VALVE-STEM-PROTECTOR HOOD.

1,332,347.

Specification of Letters Patent. Patented Mar. 2, 1920.

Application filed April 16, 1919. Serial No. 290,453.

To all whom it may concern:

Be it known that I, WILLIAM P. LOWTHER, a citizen of the United States, residing at Spokane, in the county of Spokane and State 5 of Washington, have invented new and useful Improvements in Valve-Stem-Protector Hoods, of which the following is a specification.

This invention relates to an improved 10 protecting device for that portion of an explosion engine valve stem lying between the guide therefor and the closure thereof.

My invention is adapted for use in connection with either an exhaust valve stem, 15 an intake valve stem, or both.

In connection with an exhaust valve stem, one of the main features of my invention is 20 to prevent the stem from "sticking" in its guide and thereby preventing the closure from engaging the valve seat. A further object is to protect the valve stem, throughout its exposed length, from the heating action of exhaust gases flowing out through the exhaust passage, and which gases would 25 otherwise play upon and seriously affect the stem.

In connection with the intake valve, it is 30 an object of my invention to prevent air leakage into the intake passage, from between the stem and the guide, which leakage, on a loose-working stem, is sufficient to materially weaken the mixture.

In either utility of my invention it is an object to provide a protector of sufficient 35 size to surround the valve stem and a portion of its guide with a dead air body, the function of which, in connection with the exhaust valve stem is to reduce superheating of the stem, and in connection with the intake valve stem, the function is to present this dead air body to any leakage ingress 40 thereby neutralizing the effect of the same before the flow can enter the intake passage.

It is a feature of my invention to provide 45 a protecting hood for the performance of these various functions, and a novel portion of said hood consists in an inturned sharp edge for engagement with the stem guide, 50 peripherally thereof.

Other objects and features of this invention will be more fully described in connec-

tion with the accompanying drawing and will be more particularly pointed out in and by the appended claims.

55

In the drawing:

Figure 1, is a sectional view of a portion of an engine structure illustrating an intake valve provided with the device of my invention; the same being shown in section.

60

Fig. 2 is a sectional view showing the device of my invention applied to an exhaust valve.

65

Fig. 3 is a sectional view on line 3—3 of Fig. 1.

65

Fig. 4 is a vertical sectional view of my improved protecting device detached from the valve stem.

70

Like characters of reference designate similar parts throughout the different figures of the drawing.

As illustrated, 1 designates the intake valve chamber of an explosion engine and 2 designates the passage chamber, ingress of the mixture being through opening 3. An intake valve closure 4 is shown coacting with a seat 5 and provided with a stem 6. The stem 6 extends through a guide 7 toward the operating mechanism which is not shown.

80

In Fig. 2, I have illustrated an exhaust valve chamber 8, having an exhaust valve 9 coacting with the seat 10. The exhaust chamber 11 communicates to an exhaust outlet 12. The valve closure 9 has a stem 13 which extends through a guide 14 toward the operating mechanism therefor, not shown.

85

The device of my invention takes an identical form when used either for an exhaust or an intake valve. As illustrated, my protecting device is in the form of a hood having a contracted neck portion 15, adapted to snugly fit the valve stem 6 or 13, with its end in abutting edgewise engagement at 16, against the lower edge of the valve closure. A pin 17 may serve to positively unite the hood with the stem. From this neck portion 15 the device is appreciably enlarged, as at 18, in such a manner as to extend in relatively considerable spaced relation from both the stem and the guide. The lower edge 19 is inturned and is also preferably sharpened so as to engage the periphery of the guide 7 with a proper working

90

95

100

clearance. This engagement will not be such that it would be air-tight but it will be sufficiently snug so that the dead air body would present a considerable inertia to be overcome by any air which might gain ingress from between the stem and the guide.

It will now be clear that the protecting device occupies the same relation to the parts in both the intake and the exhaust valves, the edge 19 extending sufficiently below the upper edge of the guide so that the protecting device will completely inclose what would otherwise be the exposed portion of the valve stem. Too much stress cannot be laid upon the complete inclosure of that portion of the valve stem between its guide and closure, especially in the case of an exhaust valve.

In an exhaust valve, the gases frequently condense and mix with the lubricant and there is a chemical reaction which destructively affects the valve stem. Not only the lubricant but the condensed gases are entirely prevented from reaching the valve stem when the same is equipped with my device. Normally, the exhaust valve stem is subjected to a very severe heating action when the burnt gases flow out through the exhaust passage, which is entirely avoided by the use of my invention.

Carbon deposits, especially on the exhaust valve stem and its guide will frequently cause an interruption or stoppage before the stem has completely reached a closing position. This leaves the exhaust valve closure open, very slightly, and the force of the explosion on the piston is consequently weakened. By reason of the fact that my protector telescopes the guide outwardly and reaches for a considerable distance below the top of the guide, it will be seen that deposits cannot accumulate on the stem. Furthermore, my improved device only has a minute annular peripheral engagement with the guide, and thus if carbon deposits on the guide, it will be continually scraped off down to the diameter of the sharp edge of the hood, thereby preventing any accumulation of the deposit beyond such diameter.

While there will be a deposit of carbon on the guide, this constant deposit will serve a utility, in the case of my invention, because it will act as a "fill" so that irrespective of the difference of contraction as between the hard metal hood and the cast iron guide, there will always be a good working fit. It is the purpose of my invention to make the hood of hard metal and case harden the edge 19.

By reason of the fact that the body of the hood 18 is much larger than the guide, and in view of the fact that the telescoping relation is established wholly by the inturned sharp edge, it will be seen that no form of deposit could ever wedge between the guide

and the hood and retard the latter from free movement lengthwise of the former because the hood, above the sharp edge is in spaced relation to the guide.

The enlarged sleeve-like hood provides for such a considerable dead air space that even during slow operation of an engine, when it is considered how rapidly the intake valve opens and closes, no air suction could induce anything like a flow of air from between the intake valve stem and its guide because the inertia of the dead air body would not be overcome until the valve had again closed.

It is believed that the novelty and utility of my invention, both in the combination, and as an article of manufacture, will be clear from the foregoing description, and while I have herein shown and described one specific form of my invention, I do not wish to be limited thereto except for such limitations as the claims may import.

I claim—

1. In a protecting device for that portion of an explosion engine valve stem between the closure and the guide, a sheet metal hood fixed to and housing such portion of the stem and extending about and having an inturned annular sharp edge slidable connection with the guide for a sufficient distance to completely house such portion of the stem irrespective of the position of said closure.

2. In a protecting device for that portion of an explosion engine valve stem between the closure and the cast iron guide, a hood fixed to said stem in abutting relation to said closure and the remaining portion extending about said stem and about said guide for a sufficient distance to house such portion of the stem irrespective of the position of said closure, and said hood being of hard metal and having an inturned hardened sharp-edged flange engaging the periphery of said guide with a scraping action whereby the "fill" of the deposits on the periphery of said guide will assure a close fit operative slidable connection of said edge against said guide irrespective of the difference of co-efficiency of contraction of said hood and guide.

3. In a protecting device for that portion of an explosion engine valve stem between the closure and the guide, a sheet metal hood adapted to be fixed in tight relation against the stem and adapted to engage said closure and the remainder of the hood being enlarged with respect to the stem and having an inturned annular edge adapted to slidably engage the periphery of said guide to present a relatively considerable dead air body in said hood resisting ingress or egress passage of air and particles from between said stem and guide.

4. In a protecting device for that portion of an explosion engine valve stem between the closure and the guide therefor, a hood

having a contracted neck tightly fitting about said stem and being secured to said stem, the remainder of said hood being enlarged into widely spaced relation to said 5 stem and guide and having an inturned sharpened edge slidably engaging the periphery of said guide a sufficient distance

theralong to inclose said stem irrespective of the position of said closure, whereby the dead air body in said hood is presented to 10 resist ingress or egress from between said stem and guide.

WILLIAM P. LOWTHER.
